DESIGN FOR AN ADJUSTABLE SCREEN DOOR PANEL OR SIMILAR ARTICLE

Augusta A. Klingbiel, Los Angeles, Calif.

Application October 15, 1946, Serial No. 133,964

Term of patent 3½ years

(Cl. D13—2)

To all whom it may concern:

Be it known that I, Augusta A. Klingbiel, a citizen of the United States, residing at Los Angeles, in the county of Los Angeles and State of California, have invented a new, original, and ornamental Design for an Adjustable Screen Door Panel or Similar Article, of which the following is a specification, reference being had to the accompanying drawing, forming part thereof.

able screen door panel or similar article, embodying my new design, the opposite face being plain; and

Figure 2 is a view in end elevation.

I claim:

The ornamental design for an adjustable screen door panel or similar article, as shown.

AUGUSTA A. KLINGBIEL.
